UNITED STATES PATENT OFFICE.

RICHARD MARMADUKE JONES, OF NORTHAMPTON, ENGLAND, ASSIGNOR TO UNITED SHOE MACHINERY CORPORATION, OF PATERSON, NEW JERSEY, A CORPORATION OF NEW JERSEY.

STEAM GENERATOR.

Application filed December 26, 1922, Serial No. 608,935, and in Great Britain January 3, 1922.

This invention relates to steam generators. While the illustrated apparatus is more particularly intended for use in connection with welt sewing, outsole stitching and like machines employed in the manufacture or repair of boots or shoes, the invention may advantageously be utilized in connection with other machines and for other purposes for which steam is required, such, for example, as heating glue or heating water.

The invention, regarding it broadly, aims to produce a steam generating apparatus which will be safe, economical and efficient.

An important object of the invention, considering it in its application to shoe machinery, is to avoid certain disadvantages which exist in the customary way of heating hooked needle wax thread or like sewing machines such as are used in welt-sewing, sole-sewing, or outsole-stitching, where factory steam pressure is not available. Customarily, in such cases, a pressure heating system supplied with steam from a small boiler containing a supply of water is used and this results not only in the equipment for this purpose being costly and involving regular official boiler inspection but much time is lost in heating up a cold machine before beginning work.

There will be described, purely by way of illustration, a form of the invention which, as applied to such sewing machines as last referred to, has, *inter alia*, the advantages of such safety even when used by inexperienced operators as to render official boiler inspection unnecessary, of costing but a fraction of the cost of the customary equipment referred to, of enabling a machine to be started up in a fraction only of the time requisite with the usual equipment, of being capable of being filled to replenish losses due to evaporation and leakage without interrupting its action, and of being free of that liability to irregular and imperfect operation, owing to water locks of condensed steam in the heating conduits of the machine, to which the customary equipment is subject.

The above and other objects of the invention and its features will become fully evident from a consideration of the example above referred to, which will now be described with reference to the accompanying drawings and said features will be particularly pointed out in the appended claims.

In the drawings:

Figure 1 is an elevation, partly in section, 55 of a steam generator according to the invention, and

Figure 2 is a sectional plan view on the line 2—2 of Fig. 1.

Like reference characters indicate like 60 parts in the figures of the drawings.

In the construction shown in the drawings, water from a tank 50 passes through a pipe 50^a, 51, in which is a check-valve 52, to an upright pipe 53. Surrounding the upright 65 pipe 53 is an annular gas burner 54 which supports an asbestos lined chimney 55. The pipe 55 has formed on it a flange 56 which supports a superheating labyrinth 57 which is clamped against the flange 56 by a cap nut 70 58 threaded on to the upper end of the pipe 53. The passages 59 in the labyrinth are covered by a plate 60, which may be of thin copper, fixed to the labyrinth by bolts 61. Resting on the heads of the bolts 61 is a cover 62 75 from which projects a chimney 63. The entrance into the passages in the labyrinth is through an opening formed in the side of the upper end of the pipe 53 and the exit is through a pipe 64 which passes up through 80 the chimney 63 and serves as a steam supply for those parts of the machine, or any other apparatus that it is desired to heat. The return pipe from the machine, or other heated apparatus, is shown at 65. This pipe is connected to a small reservoir 66 which has at 85 its upper end a pipe 67 leading into a large open tank or reservoir 50 and at its lower end a pipe 68 forming, with the pipe 50^a, a U-tube connection between the small reservoir 90 66 and the large reservoir 50. This arrangement results in the hot condensed steam being collected and fed to the generator in some measure separately so that the cold water from the large reservoir is, generally speaking, only added to the hot water from the chamber 66, as the latter flows to the generator, as needed to replace shortage of water due to leakage, evaporation, etc. This is because the condensed steam returning from 100 the pipe 65 tends to raise the level of the water in the small reservoir 66 and in order to maintain the levels in both the small reservoir 66 and the large reservoir 50 equal, the water in the connecting pipe 68, 105 between the two, flows towards the T-connection 69. As the circulation to the boiler is practically continuous, this warm

water in the T-connection enters the pipe 51 leading to the boiler before it has much opportunity to rise and mix with the water in the large reservoir 50. During continued operation, however, the contents of the tank 50 become necessarily also somewhat heated owing to the condensation thereon of steam escaping from the pipe 67 and also owing to the imperfect action of the U-tube in separating the water from the two sources of supply, due both to diffusion and to the inevitable surging in the pipes on sudden closing of the check valve 52.

The illustrated steam generator operates in the following manner: Water is poured into the tank 50 and flows through the pipes 50^a and 51, through the check valve 52 and into the upright pipe 53, and then, as the filling is continued, it flows through the pipe 68 into the small reservoir 66. When the water level is still below the top of the chimney 55 the filling is stopped, in order that no water may reach the superheating labyrinth 57. When the gas burner 54 is lighted, steam is soon generated in the upright pipe 53, and this is then superheated as it passes through the labyrinth 57. The steam then passes through the outlet or steam supply pipe 64 to the apparatus to be heated. The condensed steam returns through the pipe 65 together with some uncondensed steam. As previously explained, the condensed steam passes through the small reservoir 66 and the pipes 68, 51 and through the check valve 52 and is then reconverted into steam. The circulation through the system is thus continued as long as the burner is lighted. Most of the returned steam from the pipe 65, that is not already condensed, is condensed in the upper part of the small reservoir 66 or in the pipe 67 but such as is not, passes out into the atmosphere from the lower end of the pipe 67 and part of this is condensed when it strikes the colder water in the large reservoir 50.

It will be seen that both the intake and outlet of the circulating system is open to the atmosphere and, accordingly, only slight pressure, due to the friction of the steam in passing through the apparatus to be heated, can be developed. While this slight pressure is sufficient to close the check valve 52 and prevent circulation in the reverse direction, it is far too low to make the use of a safety valve necessary. Accordingly, this steam generator is particularly useful for putting into the hands of those unexperienced in the operation of steam boilers, it being absolutely safe under all conditions and requiring no official boiler inspection, while the usual steam generators for the work mentioned develop from 20 to 30 pounds to the square inch of steam pressure.

Another advantage is due to the fact that the generator can be filled at any time to replenish losses due to evaporation, without in-

terrupting its operation, by merely adding water to the large reservoir 50.

Furthermore, the generator is even more effective than those using steam under the pressures mentioned, for the reason that the temperature of the superheated steam can easily be made higher than the steam generated in the usual pressure system, and the superheated steam, expanding similar to a gas as it is heated (and being free to expand because the outlet is open to atmospheric pressure), circulates (because of the difference in pressure between the generator and the atmosphere) more rapidly than steam under pressure where circulation can take place only as rapidly as condensation occurs because the inlet and outlet are under equal pressures. Furthermore, superheated steam can not condense in the passages of the heated apparatus until it has lost all of its superheat. Thus, by taking advantage of these two properties of superheated steam in the present construction, the formation of pockets of water in the apparatus being heated is extremely rare after the working temperature is reached. Furthermore, when such pockets do form while getting the apparatus to working temperature or at any other time, the pressure automatically increases slightly in the generator above atmospheric pressure until the water is blown out (the check valve 52 preventing the pressure from working in the opposite direction). The pressure then becomes lowered automatically to the usual slight pressure necessary to produce normal circulation.

Having described my invention, what I claim as new and desire to secure by Letters Patent of the United States is:—

1. A generator for superheated steam, having, in combination, a water reservoir open to atmospheric pressure, a source of heat, a steam generating portion in which only a limited quantity of water can be converted into steam at one time by heat supplied from said source, said conversion occurring at and slightly below the water level of the reservoir, a connection between the reservoir and the steam generating portion, a steam superheating portion containing a connected series of tortuous passages located above the steam generating portion, a connection between said portions, a cover common to all of said tortuous passages made of material of high heat conductivity and located on the underside of the superheating portion so as to be exposed to the source of heat, and an outlet for superheated steam at the end of the series of tortuous passages farthest removed from the connection to the steam generating portion.

2. A generator for superheated steam, having, in combination, a water reservoir open to atmospheric pressure, a source of heat, a steam generating portion in which only a limited quantity of water can be converted into

steam at one time by heat supplied from said source, said conversion occurring at and slightly below the water level of the reservoir, a connection between the reservoir and the 5 steam generating portion, a check valve in said connection opening toward the generator, a steam superheating portion containing a connected series of tortuous passages located above the steam generating portion, a 10 connection between said portions, a cover common to all of said tortuous passages made

of material of high heat conductivity and located on the under side of the superheating portion so as to be exposed to the source of heat, and an outlet for superheated steam at ¹⁵ the end of the series of tortuous passages farthest removed from the connection to the steam generating portion.

In testimony whereof I have signed my name to this specification.

RICHARD MARMADUKE JONES.
